(57) **CLAIM**

The ornamental design for a controller for a compression device, as shown and described.

DESCRIPTION

FIG. 1 is a top perspective view of a controller for a compression device.

FIG. 2 is a top plan view of the design shown in FIG. 1.

FIG. 3 is a bottom plan view of the design shown in FIG. 1.

FIG. 4 is a side elevational view of a first side of the design shown in FIG. 1.

FIG. 5 is a side elevational view of an opposite second side of the design shown in FIG. 1.

FIG. 6 is an end elevational view of one end of the design shown in FIG. 1; and,

FIG. 7 is an end elevational view of an opposite end of the design shown in FIG. 1.
